COMBINATION HOUSEHOLD MEASURING AND DISPENSING DEVICE

Lloyd W. Cottrell, St. Clair Shores, Mich.

Application November 18, 1949, Serial No. 6,133

Term of patent 14 years

(Cl. D52—1)

To all whom it may concern:

Be it known that I, Lloyd W. Cottrell, a citizen of the United States of America and a resident of St. Clair Shores, county of Macomb, State of Michigan, have invented a new, original, and ornamental Design for a Combination Household Measuring and Dispensing Device, of which the following is a specification, reference being had to the accompanying drawings, forming a part hereof:

Fig. 1 is a perspective view of a combination household measuring and dispensing device, showing my new design;

Fig. 2 is a side elevational view of said device;

Fig. 3 is an end elevational view of said device as seen from the right side in Fig. 2;

Fig. 4 is a perspective view of my measuring and dispensing device, the view disclosing one member of the said device in a position different from that shown in Fig. 1.

I claim:

The ornamental design for a combination household measuring and dispensing device, as shown.

LLOYD W. COTTRELL.
